UNITED STATES PATENT OFFICE.

JOHN GITZ, OF ORANGE, NEW JERSEY.

FAN-ACTUATING MEANS.

1,162,154.

Specification of Letters Patent. Patented Nov. 30, 1915.

Application filed November 16, 1914. Serial No. 872,397.

To all whom it may concern:

Be it known that I, JOHN GITZ, a subject of the King of Hungary, residing at Orange, in the county of Essex and State of New Jersey, have invented certain new and useful Improvements in Fan-Actuating Means, of which the following is a specification.

This invention relates to certain new and useful improvements in mechanical fan-actuating means.

The primary object of the device is to provide actuating means for a revoluble hand fan which is of light weight and is readily operated with the desired rapidity by a slight pressure exerted thereon by a finger 15 or the thumb of the holding hand.

A further object is to provide actuating means for a revolving hand fan that is easy to manufacture and is highly efficient in mechanically setting the air in motion being provided with driving mechanism actuated by the hand of the person supporting the device.

A still further object is to provide in connection with a revolving hand fan a rack and pinion actuating means for the fan adapted for actively actuating the same upon a downward movement imparted thereto by the hand of the operator holding the device.

With these general objects in view and others that will appear as the nature of the invention is better understood, the same consists in the novel combination and arrangement of parts to be hereinafter more fully described, illustrated in the accompanying drawings, and set forth in the appended claims.

In the drawings forming a part of this application and in which like-designating characters refer to corresponding parts throughout the several views, Figure 1 is an elevational view of the device with a portion of the mechanism casing removed. Fig. 2 is a central longitudinal sectional view thereof. Fig. 3 is an elevation of the driving means of the device with adjacent parts shown in section and the elements being positioned ready for actuation. Fig. 4 is a similar view with the elements positioned as found at the end of an operative movement thereof. Fig. 5 is a side elevation of the elements shown in Figs. 3 and 4. Fig. 6 is a transverse sectional view upon line VI—VI of Fig. 5. Fig. 7 is a perspective view of the mechanism frame of the device, and

Fig. 8 is a different form of fan that may be employed.

Referring more in detail to the drawing it will be noted that the invention broadly 60 consists in a fan 10 carried by a casing 11 which is provided with suitable mechanism for revolving the fan, the said casing having a removable side 12 and an end handle portion 13 and by which the device is held by 65 the operator during the fanning operation.

The casing 11 at the end thereof opposite the handle 13 has a tubular lateral extension 14 axially of which a shaft 15 is journaled for revolution being provided with a 70 pinion 16 within the casing and having one end 17 extending exteriorly thereof and upon which the fan 10 is rigidly secured by means of a winged set nut 18. The fan 10 is preferably formed of a plurality of separate blades 19 here illustrated as six in number and being separately journaled upon the shaft end 17 so that upon releasing the nut 18, the fan blades may be folded or closed together in a manner that will be at once 80 apparent from Figs. 1 and 2 of the drawings. If desired, hooks 20 may be pivoted as at 21 to the peripheral edges of the separate blades and engaged with staples 22 upon the peripheral edges of the adjacent 85 blades, thus assisting the nut 18 in positioning the blades accurately spaced apart.

A driving shaft 23 is journaled longitudinally of the casing 11 in opposite brackets 24 and 25 positioned respectively adjacent 90 the tubular and handle ends of the casing. The driving shaft is provided with a terminal pinion 26 in constant mesh with the pinion 16 of the fan shaft 15 and whereby as will be apparent, the revolving of the 95 driving shaft 23 results in revolving the fan 10.

A stub shaft 27 is journaled in a bracket 28 and an arm 29 of the casing bracket 25 and is provided with a large gear 30 in constant mesh with a small pinion 31 positioned adjacent the handle end of the driving shaft. A power shaft 32 is journaled in opposite posts 33 carried by the base 34 of the casing bracket 25 and has a large gear 35 secured 100 thereon which is in constant mesh with a pinion 36 upon the handle end of the stub shaft 27. By this arrangement it will be seen that any rotation of the power shaft 32 and its gear 35 will turn the stub-shaft 27 105 and by means of the stub shaft pinion 36 and whereupon the gear 30 of the stub shaft will

impart movement to the driving shaft 23 by means of the driving shaft pinion 31.

One of the essential features of the invention is the actuating mechanism for the 5 power shaft 23 and the same will now be described.

A longitudinal reciprocating rack 37 is 10 slidably mounted in a slot 38 of a laterally projecting arm 39 of the casing bracket 25 and has an actuating lever 40 pivotally connected by the bolt 41 to the top thereof while the inner end of said lever is pivoted as at 15 42 to a projecting post 43 of the bracket arm 39 and the outwardly projecting free end of the lever is provided with a thumb or finger 20 plate 44. An expansion spring 45 encircles the rack 37 and is positioned between the arm 39 and lever 40 and is adapted to hold the rack in a normal projected position 25 and is formed with a larger convolution adjacent the arm 39 than those which are positioned adjacent the lever 40 which permits an oscillation of the rack 37 within the slot 38 at its extreme outer and inner limit of its stroke as hereinafter described.

Spaced guide fingers 46 are carried inwardly projecting from the casing bracket 25 and the rack 37 is adapted to reciprocate therebetween, opposite side plates 47 upon the rack being adapted to slide upon the flat 30 end faces 48 of the said fingers during the inward or retracting movement of the rack and at which time the teeth 49 of the rack are in mesh with a gear 50 of the power 35 shaft 32, a leaf-spring 51 carried by the casing bracket 25 being adapted to resiliently bear against the rack 37 at a point between the fingers 46 and hold the toothed rack in engagement with the said power shaft pinion 40 during the inward movement of the rack.

An inward movement of the rack being 45 effected by pressing the thumb or finger of the hand upon the plate 44 when the handle 50 13 is grasped in the hand, the power shaft 32 will be thus revolved which in the manner hereinbefore described will result in revolving the fan shaft 15 and thus turning the fan 10. When the rack 37 has nearly 55 reached its extreme inward limit of its stroke, the inclined end 52 of the rack will be brought in contact with the convex surface of a leaf spring 53 mounted upon the casing 11 and a slightly continued inward 60 movement of the rack 37 will result in a forcing of the lower end of the rack in a swinging movement by means of the said engagement of the spring 53 and rack end 52, which movement will be in a direction 65 away from the power shaft 32. This swinging movement of the rack end places the rack plates 47 in a plane to be received within the inner grooves 54 of the fingers 46 when the spring 45 projects the rack 37 outwardly to its normal position, and at which 65

time the rack teeth are out of engagement with the power shaft pinion as best illustrated in Fig. 4.

By this detailed description of the elements of the device and the separate operations thereof, the complete operation of the device will be at once apparent. It is to be understood that the blades of the fan are rigidly secured to the fan shaft by the nut 18 and that the removable side 12 of the casing is secured in place as illustrated in Fig. 2 and at which time the actuating lever 40 projects through a side slot 55 of the said casing side 12.

Pressure upon the plate 44 inwardly moves 80 the rack 37 and thereby turns the power, stub, driving, and fan shafts, and at its extreme inward limit of its movement its return reciprocation is changed to bring the rack out of engagement with the power shaft 85 pinion 32 and to freely move to its normal outward position, it being thus understood that the inward movement alone effects the operation of the fan while the outward movement thereof is only a return idle movement 90 of the rack, although, the fan by its own momentum continues its revolutions notwithstanding the interrupted or pulsating manner of applying the power thereto.

In Fig. 8 of the drawings a disk 60 is provided which is employed as the fan member and is secured to the outer end of a driving shaft 23' similar to the driving shaft 23 of the preferred form of construction, a similar casing 11' being also employed and all 100 of the driving and remaining mechanism being identical to that hereinbefore described.

While the form of the invention herein shown and described is what is believed to be the preferred embodiment thereof, it is nevertheless to be understood that minor changes 105 may be made without departing from the spirit and scope thereof as claimed.

What I claim as new is:—

1. A fan actuating means comprising a 110 shaft, a pinion secured thereto, a toothed rack mounted for oscillation and reciprocation engageable with said pinion only during the inward shifting of said rack, manual retracting means and automatic projecting 115 means for said rack, fingers positioned at opposite sides adjacent said rack and having flattened outer faces and oppositely notched inner walls, there being side projecting plates upon said rack adapted for engaging 120 said faces and notches during the opposite reciprocations of the rack, a deflecting spring for said rack positioned in the line of movement of the lower end thereof, and resilient means slidably engaging said rack between 125 the said fingers, to force the same into engagement with the pinion, and oppositely positioned with respect to said pinion.

2. In a fan device, a power shaft, an automatically projected rack engageable there- 130

with and mounted for oscillation and reciprocation, resilient means for engaging said rack with said shaft, a deflecting spring for said rack operable at the extreme limit of the 5 inward movement of said rack, and guiding means for said rack including a pair of guide arms between which the rack moves, said guide arms being provided with slots adjacent their ends, there being lugs on said 10 rack engageable with the ends of the guide

arms as the rack moves in one direction and engageable in the slots as the rack moves in the opposite direction.

In testimony whereof I affix my signature in presence of two witnesses.

JOHN GITZ.
